UNITED STATES PATENT OFFICE.

EDWARD J. McCLELLAN, OF NEW YORK, N. Y., ASSIGNOR TO THE GARVIN MACHINE CO.,
A CORPORATION OF NEW YORK.

CHUCK.

1,305,138.

Specification of Letters Patent. Patented May 27, 1919.

Application filed August 17, 1917. Serial No. 186,694.

To all whom it may concern:

Be it known that I, EDWARD J. McCLELLAN, a citizen of the United States, residing at the city of New York, in the borough of Manhattan and State of New York, have invented 5 certain new and useful Improvements in Chucks, of which the following is a full, clear, and exact description.

This invention relates to lathe-chucks of 10 the type in which the jaws of a chuck are actuated by a common member which has inclined surfaces in sliding engagement with correspondingly inclined surfaces on the jaws whereby a linear reciprocation of the 15 common member will cause a simultaneous radial movement of the jaws.

One object of the invention is to provide 20 the common member and jaws with engaging parts which are so constructed that a central pull will be exerted on each of the jaws to move it toward its closed position; or in other words, the direction of the pull will be parallel to the longitudinal axis of the 25 jaw.

Other objects of the invention are to provide 30 engaging parts which will remain in firm contact during the actuation of the jaws, will not be subject to undue wear and which will be of sufficient strength to sustain the stresses to which these parts are subjected when the work is gripped in the 35 chuck.

With these and other objects in view, the invention consists of a common member or 40 block having a plurality of axially directed T-shaped recesses and actuating jaws with longitudinal extensions from their lower ends of a shape to fit into the T-shaped grooves and to slide therein, the surfaces of 45 the extensions from the jaws and the T-shaped grooves having their contacting surfaces inclined to the horizontal whereby a linear reciprocation of the common member will cause a radial movement of the jaws.

The invention also consists of the constructions and combinations hereinafter set forth in the detailed description in conjunction with the accompanying drawings and pointed out in the appended claims.

In the drawings:

Figure 1 is a front view of the chuck constructed in accordance with the principles of the invention;

Fig. 2 is a top view thereof;

Fig. 3 is a central vertical section;

Fig. 4 is a front elevation of one of the actuating jaws;

Fig. 5 is a detail showing in perspective the actuating wedge or block;

Fig. 6 is a detail showing in perspective 60 one of the actuating jaws; and

Fig. 7 is a detail showing in perspective 65 one of the false jaws.

The head of the chuck, which is indicated 70 1, is similar to chucks of this character, and consists of an annulus or ring to the rear face of which is secured a face plate 2 which may be threaded as at 2' to secure it in place upon the threaded nose of a lathe-spindle. The face plate may be of any suitable shape 75

and one type of face plate is shown in Fig. 3 which is secured to the head 1 by means of bolts 3; in Fig. 2 a slightly modified form of face plate is shown. The front face of the head 1 is provided with a plurality of rectangular recesses, which recesses are radially disposed and are adapted to receive the rectangularly-shaped actuating jaws 4, the recesses preferably being provided with guides or ways 5 upon which the jaws slide. Each 80 of the jaws 4 has a central vertical recess or groove 7 cut in its front face. False jaws 8 which are adapted to grip the work are each provided with a ridge or projection 9 which fits into the recess 7 similar to a mortise 85 joint. The front face of the actuating jaw, as well as the rear face of the false jaws 8, are also provided with a horizontal recess into which a block or key 10 fits, which block is held in place by a screw 10'. The false 90 jaws are secured to the actuating jaws by bolts 11, this part of the construction being 95 common to chucks of this character.

The wedge or block for actuating the jaws 100 comprises a cylindrical block 12 which has axially-directed T-shaped grooves 13 cut in its periphery in each of which grooves a T-shaped extension 14 on one of the actuating jaws 4 is adapted to slide. As will be clear from Fig. 5, the walls of the T-shaped slots 105 are inclined to the axis of the block and the engaging walls of the T-shaped extension 14 are correspondingly inclined so that a linear reciprocation of the block 12 within the head will cause a radial movement of the 110 actuating jaws. The cylindrical block 12 is preferably of a size to have a sliding fit in the central opening through the head 1, as is clear from Fig. 3, and the block is also provided with a central opening in which is

mounted a boring bar bushing 17. The rear end of the central opening through the block 12 is threaded as at 18 to which is secured a draw-bar or tube 19 for reciprocating the block, it being understood that this bar extends through the hollow spindle of the lathe and is connected to the usual means for operating it. The front face of the chuck is covered by a guard or protector plate 20, which fits into a recess in the front face and is flush therewith. This plate rests against the actuating jaws and is provided with radial slots 21, the false jaws 8 being recessed as at 22 to fit around the slots 21 and to hold the plate against movement.

The manner in which the chuck operates is obvious from the previous description; *i. e.*, a linear reciprocation of the block 12 within the chuck head will cause a radial movement of the jaws either to their opened or closed position, depending upon the direction of movement of the block. When the jaws are moved inwardly to their closed position, the upper surfaces of both legs of the T-shaped extension 14 of an actuating jaw will bear against the corresponding walls of one of the T-shaped grooves 13 within the block 12, and serve as wedges or teeth to cause the jaws to move, and since the legs of the T-shaped extensions are disposed upon each side of the longitudinal axis of the jaws, the pull exerted by the block to cause each of the jaws to grip the work will be a central pull; *i. e.*, one parallel to the longitudinal axis of the jaw which will cause the jaws to grip the work firmly without any tendency for a side thrust upon the jaws.

It will also be apparent that with a T-shaped engaging part on each of the actuating jaws, the two arms forming the top of the T will distribute the load between them which will prevent them from becoming unduly worn or from fracturing when subjected to hard usage. When the block 12 is reciprocated to move the jaws outwardly, the flat bottom face of the T-shaped extension on each of the actuating jaws will slide

over the bottom of the T-shaped grooves 50 in the block and also cause a positive actuation of the jaws in this direction.

Another advantage of the construction described is that the protector plate 20 and the boring bar bushing 17 effectually prevent any chips or any other foreign matter from entering the operating parts of the chuck. This will be clear from Fig. 3, from which it will be seen that the bushing 17 is rigidly secured to the protector plate 20, while the cylindrical block 12 is slidingly mounted upon the bushing. When, therefore, the sliding block 12 is moved rearwardly, the bushing will not be displaced, and will serve as a casing to prevent any chips or other matter which enter through the hole in the protector plates from clogging the space between the front face of the block and the protector plate.

I claim:

1. In a chuck, a head comprising an annular body, a plurality of radially disposed jaws slidably mounted in said head, a block having a linearly reciprocating movement in said head, said block and jaws having engaging parts for actuating said jaws upon movement of said block, a protector plate on the front face of said head, said block having an opening therein, and a bushing in said opening secured to said protector plate.

2. In a chuck, a head comprising an annular body, a plurality of radially disposed jaws slidably mounted in said head, a block having a linearly reciprocating movement in said head, said block and jaws having engaging parts for actuating said jaws upon movement of said block, a protector plate on the front face of said head, said protector plate and block having axial openings, and a bushing in the opening of the block for the purpose set forth.

In witness whereof, I subscribe my signature, in the presence of two witnesses.

EDWARD J. McCLELLAN.
